US0D1096843S

(12) **United States Design Patent** (10) Patent No.: **US D1,096,843 S**
(45) Date of Patent: ** Oct. 7, 2025

(54) **AUDIO PROCESSOR**

(71) Applicant: **Focusrite Audio Engineering Limited**,
High Wycombe (GB)

(72) Inventors: **Peter Phillips**, Milford-On-Sea (GB);
Joshua Luke Wilkinson, Exeter (GB);
Iain James Horrocks, Southsea (GB);
Ryan Gray, High Wycombe (GB)

(73) Assignee: **Focusrite Audio Engineering Limited**,
High Wycombe (GB)

(**) Term: **15 Years**

(21) Appl. No.: **29/950,063**

(22) Filed: **Jun. 29, 2024**

Related U.S. Application Data

(62) Division of application No. 29/719,272, filed on Jan.
2, 2020, now Pat. No. Des. 1,056,955.

(30) **Foreign Application Priority Data**

Jul. 2, 2019 (EM) 006610242
Jul. 3, 2019 (GB) 6064634
Jul. 3, 2019 (GB) 6064635

(57) **CLAIM**

The ornamental design for an audio processor as shown and described.

DESCRIPTION

FIG. 1 is a top perspective view of the audio processor; FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational view thereof; and,

FIG. 7 is a left-side elevational view thereof.

The broken lines in the drawings illustrate portions of the audio processor that form no part of the claimed design.
